UNITED STATES PATENT OFFICE.

OTTO GOETZKE, OF JERSEY CITY, NEW JERSEY.

SANITARY SOAP-DISK.

1,225,323.

Specification of Letters Patent.

Patented May 8, 1917.

Application filed March 19, 1917. Serial No. 155,739.

To all whom it may concern:

Be it known that I, Otto Goetzke, a citizen of the United States, residing at Jersey City, in the county of Hudson and State of 5 New Jersey, have invented new and useful Improvements in Sanitary Soap-Disks, of which the following is a specification.

This invention relates to soap disks coated and hinged together with soap in such a 10 manner as to permit of their use but once for washing purposes being thereafter rendered useless.

The main object of this invention is to provide a sanitary soap package that can 15 be made cheaply, that is, convenient to use and when one individual use thereof is made, the disks automatically fall apart and are discarded.

The sanitary feature of my invention lies 20 in the fact that when the soap coated disks are once used they immediately disengage themselves and cannot be used again.

A further object of my invention is to provide disks of card-board or other similarly cheap material, held together in such 25 a manner so that when the soap coating thereon is washed off, the disks immediately disengage themselves, thereby avoiding the possibility of their being used again such 30 as is the case in similar articles where interlocking means are employed.

A further object of my invention is to provide a sufficient amount of soap in convenient form for individual use in public 35 places, thereby insuring cleanliness and sanitation and providing against infectious germs so often present in the ordinary soap cake.

With these objects in view the invention 40 consists in a new and novel article of manufacture consisting of two oval or round paper disks, concaved in their inner surfaces and coated on the outer surfaces and edges thereof with soap sufficient for one individual use.

Like numerals of reference indicate corresponding parts in each figure.

In the drawings Figure 1 is a plan view 50 of the soap cake disks connected together with soap in accordance with my invention.

Fig. 2 is a side elevational view of my connected soap coated disks.

Fig. 3 is a face view taken on the line 3—3 of Fig. 2 of the interior surface of one of my soap cake disks, showing the concaved center and raised outer edges.

Fig. 4 is a fragmentary cross-sectional view taken on the line 4—4 of Fig. 1 and showing the disks and soap in co-operative relation to each other.

According to my invention circular or oval disks are provided of any convenient size and preferably made of paste-board, stiffened paper or other inexpensive material.

These disks are concaved on their inner surfaces and are beveled inwardly at their edges and fitted one over the other.

Preferably the circular concaved disks in accordance with my invention are provided 76 with roughened inner edges so that when the soap coating is smeared on the outer surfaces and edges thereof the disks will engage closer to one another.

In the drawings 10 is a circular or oval 75 disk having a concaved inner central surface as shown at 11. At the inner edges of the circular or oval disk a raised surface 12 is provided to join with and meet a co-operating raised surface of another circular 80 or oval disk. The co-operating disks 10 are then coated with the soap 13 over their entire outer surfaces and edges, thereby holding the disks together until the soap is washed off when the disks automatically disengage themselves and fall apart.

A transparent soap coating may be used in covering the disks so that they may contain advertising matter.

Having thus described my invention I 90 claim:

1. A circular centrally concaved paste-board disk having an inwardly raised and beveled edge seated upon a corresponding paste-board disk both of which are coated 95 on their outer surfaces with a thin coating of soap and a film of soap closing the edges and holding the two disks together.

2. The combination of a circular concaved shell like disk loosely seated on the rim sur- 100

face of another circular concaved shell like disk and a film of soap inclosing the outer surfaces and edges thereof and holding the two shells together substantially as described.

- 5 In testimony whereof, I have signed my name to this specification at New York city,

State of New York this 13th day of March, 1917.

OTTO GOETZKE.
